(57) **CLAIM**

The ornamental design for an office chair, as shown and described.

DESCRIPTION

FIG. 1 is a perspective view generally taken from one side of the office chair showing the design;

FIG. 2 is a front elevational view thereof;

FIG. 3 is a rear elevational view thereof;

FIG. 4 is a left view thereof;

FIG. 5 is a right view thereof; and,

FIG. 6 is a top plan view thereof.

The fragmented depiction of the mesh pattern on the backrest repeats uniformly throughout the circumscribed areas.
